(57) **CLAIM**

The ornamental design for a storage container, as shown and described.

DESCRIPTION

FIG. 1 is a perspective view of a storage container.

FIG. 2. Is a front view of the storage container;

FIG. 3 is a left side view of the storage container;

FIG. 4 is a right side view of the storage container;

FIG. 5 is a rear side view of the storage container;

FIG. 6 is a top view of the storage container;

FIG. 7 is a bottom view of the storage container; and,

FIG. 8 is a section view of the storage container along the line 8-8 of FIG. 4.

The broken lines depict internal portions of the storage container which form no part of the claimed design.
